UNITED STATES PATENT OFFICE.

FLORENCE C. BIGGERT, JR., OF CRAFTON, PENNSYLVANIA, ASSIGNOR TO UNITED ENGINEERING AND FOUNDRY COMPANY, OF PITTSBURGH, PENNSYLVANIA, A CORPORATION OF PENNSYLVANIA.

SCREW DOWN FOR ROLLING MILLS.

Application filed September 7, 1923. Serial No. 661,405.

To all whom it may concern:

Be it known that I, FLORENCE C. BIGGERT, Jr., a citizen of the United States, residing at Crafton, county of Allegheny, and State of Pennsylvania, have invented a new and useful Improvement in Screw Downs for Rolling Mills, of which the following is a full, clear, and exact description.

The present invention relates broadly to the metal working art, and more particularly to screw downs for rolling mills.

An important object of the invention is to provide a screw down embodying a plurality of screws, and having a separate drive for each screw, such construction being of particular advantage in rolling thin sheets, as it enables the roll bearings to be very accurately adjusted independently of each other to compensate for unequal wearing of the roll surfaces or of the roll necks or bearings, in order that sheets of substantially uniform thickness may be obtained.

Another object of the invention is to provide a separate worm drive for each screw, including an actuating handle for each of said worm drives adjustably mounted upon a shaft, and having readily releasable means for locking said handle in any desired angular position with respect to said shaft.

In the accompanying drawings, there is shown, for purposes of illustration only, one embodiment of the present invention, it being understood that the drawings do not define the limits of the invention, as changes may be made in the construction and operation therein disclosed without departing from the spirit of the invention or scope of my broader claims.

In the drawings:

Figure 1 is a side elevation of a roll housing provided with a screw down embodying my invention;

Figure 2 is an end elevation of the structure shown in Figure 1;

Figure 3 is a plan view of the structure shown in Figure 1;

Figure 4 is a sectional view illustrating the means for releasably securing an actuating handle to its shaft, and

Figure 5 is a sectional view taken on the line V—V of Figure 4.

In the drawings there is shown a roll housing of usual construction embodying spaced

standards 2 and 3 connected at the top by transverse rods 4. Each of these standards 55 is provided with the usual window 5 in which are positioned the bearing blocks for the rolls, a roll 6 being shown diagrammatically in Figure 1.

Extending through the top of each standard is a pair of vertical screws 7 adapted to bear at their lower ends upon an upper bearing block. Mounted upon the top of the standard 2 is a casting 8, and upon the top of the standard 3 a corresponding 65 casting 9, in each of which the corresponding pair of screws 7 is journaled. A worm gear 10 is splined or otherwise secured upon the upper end portion of each screw 7, so as to permit vertical movement of the screw 70 with respect to the worm. The worm gears above each standard are positioned in different horizontal planes, this arrangement permitting the pair of gears above each standard to overlap, so that relatively large 75 gears may be employed.

Engaging each worm gear 10 is a worm 11. The worms which engage the gears above the standard 2 are mounted upon relatively short shafts 12 which extend 80 transversely of the standard, each shaft being journaled in a pair of spaced bearings 13 on an end of the casting 8, the worm carried by each shaft 12 being positioned between a corresponding pair of bearings. 85 The worms 11 which engage the gears 10 above the standard 3 are carried by relatively long shafts 14 which extend transversely across the top of the roll housing parallel to the shaft 12, each shaft being journaled 90 in a bearing 15 on an end of the casting 8 and in a pair of spaced bearings 16, similar to the spaced bearings 13, on an end of the casting 9, the corresponding worm 11 being positioned between said spaced 95 bearings 16.

Each of the shafts 12 and 14 has a reduced end portion 17 overhanging the outer side of the standard 2. Keyed upon such reduced end portion is a bearing 18 provided 100 in its periphery with a series of recesses 19. A handle 20 is formed at one end with a hub 21 to receive the bearing 19, opposite ends of the hub being engaged by washers 22 on the reduced portion 17, whereby the 105 handle 20 is prevented from moving longi-

tudinally of the shaft, but may be rotated with respect thereto. For locking the handle 20 in any desired angular position with respect to the shaft upon which it is mounted, there is provided a locking pawl 23 extending through an opening in the hub 21, the free end of said pawl being adapted to engage in any one of the series of recesses 19 in the bearing 18. The pawl 23 extends longitudinally of the handle 20 and is adapted to be actuated to release the handle from its shaft by means of a spring-pressed lever 24 pivoted to the free end portion of the handle 20, and having the opposite end of the pawl 23 pivotally connected thereto. In grasping the end of the handle 20, the lever 24 is depressed, thereby withdrawing the pawl 23 from the recess 19 with which it may be in engagement.

It will be noted that the handles 20 for actuating the shafts 12 and 14 are all arranged at the outside of the standard 2, but it will be perfectly apparent that the arrangement of the parts shown may be reversed, so as to position the handles 20 at the outside of the standard 3, if desired.

The operation of my improved screw down will be apparent. Each screw 7 may be separately operated by means of the corresponding handle 20. By grasping the end of the handle and depressing the lever 24, the handle may be released from its shaft and rotated to the desired angular position with respect thereto, and then locked in such adjusted position by releasing the lever 24 to the action of its spring. Thereafter, the handle may be moved in the opposite direction to actuate the corresponding screw. The locking arrangement between the handle and shaft permits the shaft to be positively rotated in either direction.

An important advantage of the present invention arises from the provision of separate means for actuating each screw, whereby a very fine and accurate adjustment of the roll bearings may be obtained.

Another advantage of the invention arises from the provision of a worm drive for each screw, including an actuating handle adapted to be angularly adjusted upon an actuating shaft and locked in adjusted position. This construction provides ample power for actuating the screws, and obviates the necessity for employing the usual spanner wrench and sledge hammer for this purpose.

Another advantage of the invention arises from the arrangement of the gears above each standard in different horizontal planes, whereby larger gears may be employed, thus increasing the gear ratio between each worm gear and worm.

I claim:

1. In a screw down for rolling mills, a roll

housing comprising spaced standards, a pair of vertical screws extending through the upper portion of each of said standards, a worm gear mounted upon the upper end of each screw, a pair of parallel shafts journaled upon the upper portion of one of said standards and extending transversely thereof, a second pair of shafts journaled upon the upper portion of both of said standards and extending parallel to the first pair of shafts, a worm mounted upon each of said shafts and engaging one of said worm gears, and separate means for actuating each of said shafts, substantially as described.

2. In a screw down for rolling mills, a roll housing comprising spaced standards, a pair of vertical screws extending through the upper portion of each of said standards, a worm gear mounted upon the upper end of each screw, a pair of parallel shafts journaled upon the upper portion of one of said standards and extending transversely thereof, a second pair of shafts journaled upon the upper portion of both of said standards and extending parallel to the first pair of shafts, a worm mounted upon each of said shafts and engaging one of said worm gears, and separate means for actuating each of said shafts, all of said means being located on the same side of said housing, substantially as described.

3. In a screw down for rolling mills, a roll housing comprising spaced standards, a pair of screws extending through the upper portion of each of said standards, and means for separately actuating said screws, comprising a worm gear mounted upon each screw, a worm engaging each of said gears and carried by a separate shaft journaled in said housing and a handle carried by each shaft for actuating the same, all of said handles being arranged at the same side of said housing, substantially as described.

4. In a screw down for rolling mills, a roll housing comprising spaced standards, a pair of screws extending through the upper portion of each of said standards, and means for separately actuating said screws, comprising a worm gear mounted upon each screw, a worm engaging each of said gears and carried by a separate shaft journaled in said housing, a handle journaled at one end upon each shaft and means operable from the other end of each handle for locking said handle in any desired angular position with respect to said shaft, substantially as described.

5. In a screw down for rolling mills, a roll housing comprising spaced standards, a pair of vertical screws extending through the upper portion of each of said standards, a worm gear mounted upon the upper end of each screw, the worm gears above each standard being arranged in different horizontal planes and overlapping each other, a worm

in engagement with each worm gear, and means for independently actuating said worms, substantially as described.

6. In a screw down for rolling mills, a roll housing, a plurality of screws extending through the upper portion of said housing, and means for separately actuating said screws, comprising a worm gear mounted upon each screw, a worm engaging each of said

gears and carried by a separate shaft journaled in said housing, a handle journaled

at one end upon each shaft, and means carried by each handle for locking said handle in any desired angular position with respect to said shaft, said means having associated therewith yielding means for normally maintaining it in locking position, substantially as described. 15

In testimony whereof I have hereunto set my hand.

FLORENCE C. BIGGERT, JR.
